UNITED STATES PATENT OFFICE

STEPHEN BALDYZAR, OF RACINE, WISCONSIN

RADIATOR HEATING CONNECTION FOR BOILERS

Application filed November 17, 1927. Serial No. 233,933.

The present invention relates to radiator attachments for boilers, such as for instance locomotive or stationary boilers and has for an object to provide a connection with the 5 steam compartment of the boiler for supplying steam to a radiator which may be remotely disposed with respect to the boiler and thus enable a utilization of the heat generated thereby for heating the radiators.

10 A further object of the invention is to provide a reservoir for collecting the water condensed by the cooling of the steam as the same is fed into the radiator and arranging the reservoir in a suitable position 15 with respect to the firebox of the boiler whereby to heat the water contained therein for the purpose of regenerating steam therefrom and again feeding the same back into

is arranged the water compartment 6 having fire tubes 7 extending therethrough communicating at one end with the firebox and with their opposite ends leading into the smoke box 8 at the upper end of which the stack 55 9 is mounted.

At the top of the water compartment is arranged a steam dome 10 having a pressure relief valve 11 provided therein and also having a feed pipe 12 connected therewith and communicating with a shallow container 13 disposed horizontally above the firebox 5 and immediately beneath the crown sheet 14 forming the upper outer casing of the boiler. 60 65

The container 13 is provided with a transversely extending partition 15 separating the same into separate compartments indicated

Control valves 21 may be interposed in each of the pipes 12, 18 and 20 whereby to regulate the circulation of steam therethrough.

It is obvious that the invention is susceptible of various changes and modification, without departing from the spirit or scope of the invention or sacrificing any of its advantages, and I accordingly claim all such forms of the device to which I am entitled.

Having thus described my invention, what I claim as new is:

In combination, a steam boiler provided with a steam dome, a relatively shallow container horizontally disposed above the firebox of the boiler, a partition arranged transversely of the container dividing the same into a pair of compartments, a feed pipe affording communication between one of said compartments and said steam dome, a radiator remotely disposed with respect to and above the plane of the container, a feed pipe connecting the upper portion of the radiator at one end with said first named compartment and a pipe communicating with the opposite end of the radiator and connected with said other compartment.

In testimony whereof I affix my signature.
